METHOD AND APPARATUS FOR CONTINUOUSLY ELECTROPLATING METALLIC STRIP

Ewart S. Taylerson, Pittsburgh, Pa., assignor to Carnegie-Illinois Steel Corporation, a corporation of New Jersey

Application April 28, 1939, Serial No. 270,708

6 Claims. (Cl. 204—206)

The present invention relates to electroplating and more particularly to a method and apparatus for supporting anodes within an electroplating tank.

Heretofore, in the continuous plating of metallic strip, when it was desired to replace anodes, it was necessary to suspend the plating operation, remove the metallic strip from the bath and substitute a fresh supply of anodes thereto. Similarly, when changes were made in the width of the strip being processed, the necessary changes in the number and/or arrangement of the anodes within the bath also required the suspension of the plating operation. Such suspension of the plating operation is undesirable since it is a source of lost time and consequently increases the plating costs.

Under the present invention such disadvantages are overcome.

An object of the present invention is to provide a method and apparatus for continuously electroplating metallic strip wherein the introduction of a fresh anode automatically moves all of the anodes on the supporting member so that the spent anode on the other side of the supporting member is moved into position for ready removal from the plating tank without affecting the continuity of the plating operation.

Another object of the present invention is to provide a method of supporting anodes within a plating tank wherein the anodes can be readily rearranged on their supporting member to conform with the requirements of the various widths of strip being plated without necessitating the removal of the anode supporting member from the plating tank.

A further object of the present invention, is to provide for adjustably supporting the anodes within a plating tank so that a substantially uniform current density is maintained.

Other objects and advantages will become apparent as the description proceeds and reference is had to the accompanying drawings, in which:

Figure 1 is a plan view of the present invention;

Figure 2 is a sectional elevation on line II—II of Figure 1;

Figure 3 is a sectional elevation on line III—III of Figure 2;

Figure 4 is a sectional elevation on line IV—IV of Figure 2;

Figure 5 is a sectional elevation on line V—V of Figure 2;

Figure 6 is a sectional elevation on line VI—VI of Figure 2; and.

Figure 7 is a sectional elevation on line VII—VII of Figure 2.

Figure 8 is a detailed illustration of the top of the anode; and

Figure 9 is a detailed perspective view of one of the insulated spacers for the anodes.

In the drawings, the numeral 2 represents a plating tank within which is vertically positioned and arranged a plurality of anodes 3 supported by anode bridges 4. These anode bridges extend across the top of the tank and are slidably mounted on blocks 5 rigidly secured to supporting beam members 6, and are electrically insulated therefrom by suitable non-conducting material 7.

15 The anode supporting bridges 4 are of identical construction, and for the purposes of illustration, a single bridge will be described in detail. Each bridge comprises a main body member 8 having secured thereto a conductor plate 9, which conductor plate is connected by suitable leads (not shown) to the positive pole of the plating generator (not shown). The conductor plates 9 are insulated from the end portions of the main body member 8 by suitable insulating material 10.

20 25 The center portion of the main body member 8 is provided with a metallic shim 12 for conducting current from the source of supply through plate 9 to member 8.

Secured to the main body member 8 for supporting the anodes are face plates 14 and 15. The face plate 15 is secured to the center portion of the main body member 8 and is in direct electrical contact with the metallic shim 12 so that the current supply is transmitted from the conductor plates 9 to the anodes supported on said face plate 15. The face plates 14 are of the same cross section as the plate 15 and are secured to the main body member 8 on each side of the said plate 15.

30 35 40 The plates 14 are spaced from each end of plate 15 so as to provide an air gap therebetween. Direct electrical contact between the main body member 8 and the face plates 14 is prevented by the insulating material 10 which, in combination with the air gap between plates 14 and 15, provides a neutral area at the ends of the anode supporting bridge 4 from which anodes can be suspended and maintained electrically neutral within the tank.

45 50 On the upper surface and on each end of the anode bridge 4 is a movable rack 16 engaged by a pinion 17 journalled on a shaft 18 by fixed brackets which is provided with a ratchet or handle construction 19 of conventional design. The movable rack 16 at the entry end A of the bridge is

provided with a blunt nose 20, while the movable rack at the withdrawal end B of the bridge is provided with a pawl 21.

The anodes 3 are provided at the top with a hook-like portion 22 by means of which they may be hung on the bridge 4 from the face plates 14 and 15. The anodes are not fastened to the bridge, their weight, however, is sufficient to cause their positive contact with said face plates. By reason of this slideable mounting, all the anodes on the bridge can be moved as a group by pushing on the end or outside members of the group. This permits a fresh anode to be introduced into the bath and moved on the bridge into the active plating area when needed and, in so doing, causes a mass movement of all of the anodes on the bridge thereby resulting in movement of the spent anode on the opposite end of the bridge into a position where it can be readily removed from the tank. Thus, the introduction of a fresh anode does not interfere with the continuity of the plating operation.

Such mass movement of the anodes requires continuity of contact of all the anodes on the bridge. Since it is seldom necessary to completely fill the anode bridge 4 with anodes, spacer blocks 24 are inserted between the anodes. The size of the spacer blocks depends on the number of anodes and width of strip to be processed.

It will be noted that the anode supporting bridge 4 and plating tank 2 is shown as being wider than necessary to accommodate the maximum width of strip capable of being plated in the tank. Such a construction provides a storage space at both sides of the tank. The spaces are used for the introduction of new anodes and the withdrawal of spent anodes. While these storage spaces must be of sufficient size to hold one anode each, they may, if desired, be made larger. Inasmuch as the uniformity of the tin coating is known to be critically dependent on the position of the anodes with respect to the steel strip cathode, it is apparent that only those anodes which are properly located should be made conductive; in other words, the anodes in the storage spaces must be made inactive. This is accomplished since the face plates 14 are positioned immediately above the storage spaces and said plates 14 are electrically insulated from the other members of the bridge 4 as hereinbefore described, thus the extra anodes, although supported by the bridge, are not in electrical contact with it.

As previously stated, fresh anodes are put in on one side, gradually moved across the tank and removed at the other side. As a result, the thickness of the anodes on the bridge 4 becomes progressively less from the entry end A to the withdrawal end B of the bridge due to the various degrees of electrolytic dissolution the anodes have been subjected to. In order that this decrease in thickness will not affect the anode to cathode spacing across the tank and thereby result in a variation in weight of coating from edge to edge of the strip, the withdrawal end B of the bridge 4 is moved closer to the strip than the entry end A. This adjustment of the ends of the anode bridge with respect to the strip is made possible by the slideable mounting of the bridge on the blocks 5. This adjustment maintains a uniform distance between cathode and anode faces.

Further, the width of an anode as well as its thickness, decreases during its travel across the tank. This, in effect, causes the distance between the anodes to gradually become greater to-

ward the withdrawal end B of the anode bridge and results in a tendency toward a streaky coating. The streaky condition is most prominent near that edge of the strip which is closest to the withdrawal end of the anode bridge. Since the streaky appearance is due to slight variations in coating thickness, the method requires the use of two or more plating passes, preferably an equal number, and in which the anode and bridge supporting members are so arranged that with respect to a given side of the strip, the direction of anode movement across the tank is opposite in each adjacent plating pass. In this manner, the position of the withdrawal side B of the anode bridge with relation to a given edge and side of the strip is reversed, and therefore, both halves of a given side of the strip will, in two or any even number of plating passes, be subjected to identical conditions, thus maintaining the coating uniform.

Where rather long anodes are used, there is a tendency for the current density to decrease along the length and towards the bottom of the anodes. This condition is prevented by inclining the anodes so that their lower ends are nearer the strip. The resistance to current flow through the solution between the anodes and strip cathode is thus progressively decreased along the length of the anodes. To obtain the desired inclination tapered wood cross pieces 23 are fastened in the tank near the bottom of the anodes. The anodes supported by any given bridge 4 rest against a cross piece 23 and, as the face of this cross piece is closer to the strip than are the face plates of the cooperating bridge, the anodes hanging from the bridge are forced to incline at a small angle. The cross piece 23 is tapered in order that its face will be in a vertical plane approximately parallel to that of the face plates of the cooperating bridge.

In operation, the continuous metallic strip S passes from a conductor roll (not shown) into the plating tank and downwardly through the first plating pass, around a sink roll 26 and upwardly through the second plating pass. Positioned on each side of the strip in each of the plating passes are groups of anodes of the coating metal each of which is slidably supported on an anode bridge 4. The anode bridges are shown arranged so that the entry ends of those bridges supporting the anodes cooperating with a given side of the strip are on opposite sides of the tank. For example, fresh anodes are supplied to the group of anodes cooperating with the side S' in the first or downward plating pass from the left side of the tank, while in the second or upward plating pass, fresh anodes are supplied to the group cooperating with the side S' in this pass from the right side of the tank. Similarly, with respect to the side S² of the strip, fresh anodes are shown as entering on the right side of the tank in the first plating pass and on the left side in the second plating pass. In this manner, the coating from edge to edge of the strip will be maintained uniform.

When it becomes necessary to supply a fresh anode to the active plating area, the movable rack on the entry side is operated, forcing the fresh anode along the insulated portion of the bridge and out into the active plating area and, in so doing, all of the anodes on said bridge are moved toward the withdrawal end. The spent or end anode of said group is moved to a position on the bridge where it can be contacted by advancing the rack on the withdrawal end of said bridge so

that the pawl 21 can engage the slot 25 which is cast in the top of the anode for that purpose. Retracting the rack pulls the spent anode into the insulated portion of the bridge where it can be readily removed from the tank.

The introduction of fresh anodes to the plating tanks is intermittent and periodical. The periods of introduction may be determined in advance, so that the spent anode removed upon the insertion of a fresh anode at the opposite (entry) side of the bridge will have been in service for the maximum time favorable to good plating results.

While I have shown and described a specific embodiment of the present invention, it will be seen that I do not wish to be limited exactly thereto, since various modifications may be made without departing from the scope of the invention, as defined by the following claims.

I claim:

1. In the continuous electroplating of metallic strip, the method which includes supporting a series of aligned flat-faced soluble anodes with their flat faces in adjacent parallelism with a side of the strip, progressively moving said series of anodes across and in a path inclined toward the strip, the progressive movement and inclined path aforesaid coacting to maintain substantially uniform spacing between the strip and the series of anodes as the erosion of the latter progresses, successively removing worn anodes at one end of said series, and introducing fresh anodes at the other end of said series.

2. In the continuous electroplating of metallic strip, the method which includes supporting a series of aligned flat-faced soluble anodes with their flat faces in adjacent parallelism with a side of the strip, supporting a second series of aligned flat-faced soluble anodes with their flat faces in adjacent parallelism with the same side of the strip in spaced relation to said first series along said strip, progressively moving each series of anodes across and in a path inclined toward the strip, the progressive movements and inclined paths aforesaid coacting to maintain substantially uniform spacing between the strip and the two series of anodes as the erosion of the latter progresses, the inclined paths of the two series extending toward opposite edges of the strip, successively removing worn anodes at one end of each of said series, and introducing fresh anodes at the other end of each of said series.

3. In apparatus for continuously electroplating metallic strip, a series of anodes supported transversely of the strip and substantially uniformly spaced from a side of the latter, said anodes progressively varying in cross section from a maximum adjacent one edge of the strip to a minimum adjacent the other edge thereof, and

means for moving said anodes in the direction of their decreasing cross section transversely of and toward the strip to compensate for erosion of the anodes whereby the substantially uniform spacing aforesaid is maintained.

5 4. In apparatus for continuously electroplating metallic strip, a series of anodes supported transversely of the strip and substantially uniformly spaced from one side of the latter, said anodes progressively varying in cross section from a maximum adjacent one edge of the strip to a minimum adjacent the other edge thereof, a second series of anodes supported transversely of the strip and substantially uniformly spaced from the same side of the latter, said second series being spaced along the strip from said first series of anodes, the anodes of said second series progressively varying in cross section in the same manner but opposite direction to those of said first-named series, and means for moving the anodes of each series in the direction of their decreasing cross section transversely of and toward the strip to compensate for erosion of the anodes whereby the substantially uniform spacing aforesaid is maintained.

10 5. In apparatus for continuously electroplating metallic strip, means for conveying the strip through a plurality of passes in an electrolyte, plural series of soluble anodes supported transversely of the strip and substantially uniformly spaced from the faces of the strip at each of said passes, the anodes of said series adjacent the same face of the strip in successive passes varying in cross section across said face from maximum to minimum in opposite directions, thereby compensating for decreasing width and variable spacing between the anodes of any of said series, and means for moving the anodes of each series in the direction of their decreasing cross section transversely of the strip.

15 6. In apparatus for continuously electroplating metallic strip, a series of elongate vertically disposed anodes supported transversely of the strip and substantially uniformly spaced from a face of the strip, said anodes progressively varying in cross section from a maximum adjacent one edge of the strip to a minimum adjacent the other edge thereof, means for moving said anodes in the direction of their decreasing cross section transversely of and toward the strip to compensate for erosion of the anodes and maintain the substantially uniform spacing aforesaid, and means adjacent the lower ends of said anodes inclining the lower ends thereof toward the strip during the said movement of the anodes, thereby maintaining substantially uniform current density throughout the length thereof.

EWART S. TAYLORSON.
